Notice of Allowance dated Apr. 9, 2020, issued in connection with U.S. Appl. No. 29/716,759 (11 pages).

Primary Examiner — Dana Meyrow(74) *Attorney, Agent, or Firm* — McCarter & English, LLP(57) **CLAIM**

The ornamental design for a bottle, as shown and described.

DESCRIPTION

FIG. 1 is a perspective view of a bottle showing our new design, including portions thereof shown in phantom lines which form no part of the claimed design;

FIG. 2 is a front view thereof, the rear view being substantially identical;

FIG. 3 is a right side view, the left side view being substantially identical;

FIG. 4 is a top view thereof; and,

FIG. 5 is a bottom view thereof.

The evenly-dashed broken lines in the drawings illustrate the portions of the bottle that form no part of the claimed design. The dot-dash broken lines in the drawings define the bounds of the claim and form no part thereof.
